CLAIM

The ornamental design for a support apparatus with liquid container, as shown and described.

DESCRIPTION

FIG. 1 is a top, front, left side perspective view of a support apparatus with a liquid container, showing our new design; FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

The evenly broken lines are shown for the purpose of illustrating parts of the article that form no part of the claim. The dot-dash lines represent the boundaries of the claim and form no part thereof.

1 Claim, 7 Drawing Sheets
